UNITED STATES PATENT OFFICE.

AUSTIN JEROME ROSS, OF CAMBRIDGE, ILLINOIS.

WATER-CONDUCTOR PIPE OR THE LIKE.

No. 845,577.

Specification of Letters Patent.

Patented Feb. 26, 1907.

Application filed May 14, 1906. Serial No. 316,850.

To all whom it may concern:

Be it known that I, AUSTIN JEROME Ross, a citizen of the United States, residing at Cambridge, county of Henry, State of Illinois, 5 have invented certain new and useful Improvements in Water-Conductor Pipes or the Like; and I do hereby declare the following to be a full, clear, and exact description of the invention, such as will enable others 10 skilled in the art to which it appertains to make and use the same.

This invention relates to certain improvements in sheet-metal pipes, and more particularly relates to improvements in down-spouts or rain-water conductors for buildings and the like employed to carry off the water from roofs.

An object of the invention is to provide an improved sheet-metal pipe particularly 20 adapted for use in locations exposed to low temperatures as a down-spout or rain-water conductor and wherein the seam uniting the edges of the sheet forming the pipe-section is arranged at the exterior of the pipe and is 25 so formed as to permit expansion of the pipe in case of freezing and wherein improved and simple arrangements are employed for locking the edges of the sheet at one end of the pipe-section.

30 A further object of the invention is to provide certain improvements and formations whereby an efficient and economical rain-water conductor or down-spout will be produced.

35 The invention consists in certain novel arrangements and formations of parts, as more fully and particularly pointed out and explained hereinafter.

Referring to the accompanying drawings, 40 Figure 1 is an elevation of a pipe-section formed in accordance with my invention. Fig. 2 is a perspective thereof, showing the large or locked end thereof. Fig. 3 is a cross-section showing the formation of the lapped edges of the sheet forming the pipe. 45 Fig. 4 is a longitudinal section through said lapped edges. Fig. 5 is a plan view of the pipe-section flattened out, showing the locking or anchoring tongues straightened out 50 as before, being bent out and down to lock the edges of the sheet together at the upper end of the pipe-section.

Each conductor or pipe is made of any desirable length, and the edges of the sheet 55 forming the same are preferably anchored or locked together at one end only of the

conductor, preferably the large end, while the opposite end is expandable so that it can be contracted in being forced or telescoped into the large end of a similarly-formed conductor. In other words, each down-spout or rain-water conductor when applied to a building is made up of a number of similar telescoped sections or sections united by slip-joints. 60

The conductor or pipe is formed from a blank or sheet of any suitable sheet metal, the longitudinal edges of which in the completed pipe-section are united by a seam arranged longitudinally of the conductor or 70 pipe.

One longitudinal edge 1 of the sheet is straight or flat. The opposite longitudinal edge of the sheet is, by suitable appliances doubled twice on the outer face of the sheet— 75 that is, the edge portion of the sheet is first bent back and tightly down on the outer surface of the sheet, forming the double 2—and the free edge portion 3 of the sheet is then bent forwardly and down on the double 2, thereby forming the socket or double fold opening outwardly at the edge of the sheet. There are hence three plies or thicknesses at the edge of the sheet provided with said socket, the socket being arranged on the 80 outer face of the sheet. Before the socket is formed the sheet is notched at 4, so that the socket is not formed throughout the entire length of the sheet, but terminates a distance above the lower edge of the sheet 90 equal to the distance the small or lower end of a conductor-section is capable of entering the large or anchored end of the next section. The socket, however, extends completely to the upper or opposite end of the sheet, and 95 consequently to the upper end edge of the conductor-section when formed.

When forming the blank, the same is longitudinally cut or slotted downwardly a suitable distance from and through its top edge 100 to form the similar anchoring or locking tongues 5 6. Each tongue is formed by a pair of parallel slits. The tongue 5 is formed in the flat-edge portion 1 and extends vertically or longitudinally to the top edge of the blank. The tongue 6 is similarly formed and arranged in the outer ply of the socket at the other edge of the blank. The blank having been formed as thus described and as shown in Fig. 5 is by suitable means bent 105 into cylindrical form, and the straight or flat edge 1 laps over the opposite edge and is 110

forced into the outside socket formed by the plies 2 and 3. The flat edge 1 is forced into said socket until the tongue 5 within the socket registers with the tongue 6 in the 5 outer ply of the socket at the large end of the conductor or pipe-section. The two parallel superimposed tongues are then together bent outwardly and tightly down on the outer surface of the outer ply 3 of the socket, thereby 10 anchoring or locking the ends of the sheet at the upper edge thereof and at the large or upper end of the section. After the flat end 1 has been forced completely into the socket the socket is tightly compressed to form a 15 comparatively tight seam or joint, yet one which will permit expansion of the pipe below the anchor or lock in the event of water freezing therein. As the seam of the completed pipe-section does not extend completely to the opposite or lower end of the section by reason of the notch 4, said end of the section is reduced in size, as there are only two piles of material where the flat edges of the sheet overlap, whereby the small end 20 of one section can slip into the large end of the next section until the lower end 7 of the seam engages the upper end of the seam of the adjacent section, whereby the end 7 of the exterior seam forms a stop.

25 Advantages are attained by arranging the peculiar seam described on the exterior of the pipe, so that the flat end of the sheet laps outside of the opposite edge of the sheet, whereby the interior of the conductor is free 30 of obstructions and has a smooth surface for the flow of water, and whereby a much tighter seam can be formed than if arranged within the conductor.

Having thus described my invention, what 40 I claim, and desire to secure by Letters Patent, is—

45 1. A pipe-section comprising a metal sheet having a longitudinal flat edge, and the opposite longitudinal edge doubled back on the outer face of the sheet and then doubled forwardly to form a longitudinal socket opening along the edge of the sheet and at the exterior of the pipe-section, said flat edge fitting tightly within said socket, whereby 50 the lapped portions are at the exterior of the pipe-section, said flat edge being held within said socket throughout its length by friction only, except at the large end of the section, said flat edge and socket at the large 55 end of the pipe being anchored by having por-

tions thereof bent together and exposed at the exterior of the pipe-section.

2. A pipe-section comprising a sheet-metal blank having a longitudinal flat edge and a longitudinal edge formed with an exterior 60 double fold snugly receiving the flat edge at the exterior of the section, said sheet being notched at one end of said edge provided with the double fold, whereby the double fold terminates a distance from the end edge of 65 the reduced end of the pipe-section, said flat and double-fold edges having longitudinal superimposed locking portions bent down on the exterior of the double fold at the end of the pipe-section opposite said reduced end. 70

3. A sheet-metal pipe comprising a sheet-metal blank having a longitudinal flat edge and the opposite edge formed with an exterior longitudinal double fold forming the socket snugly receiving said flat edge, said 75 flat edge and the outer ply of said fold, at one end of the section, formed with registering tongues bent together outwardly and down at the exterior of the section to form an anchor.

4. A sheet-metal pipe formed of a blank, the edges of which are united by a longitudinal seam, said edges slitted to form longitudinal superimposed tongues, said tongues bent out and down to form an anchor. 80

5. A sheet-metal pipe formed of a blank having a longitudinal flat edge, the opposite edge formed with a double fold receiving the flat edge, said flat edge and a ply of said 90 double fold cut to form parallel superimposed tongues, said tongues being together bent out and down to form an anchor.

6. A sheet-metal pipe-section formed of a blank having a longitudinal flat edge, the opposite edge formed with an exterior longitudinal double fold receiving said flat edge at the exterior of the section, said fold terminating a distance from one end of the section to form the reduced end and an exterior stop, the flat and folded edges being anchored together at the large or opposite end of the section by superimposed tongues bent out at the exterior of the pipe-section. 95

In testimony whereof I affix my signature in presence of two witnesses.

AUSTIN JEROME ROSS.
